UNITED STATES PATENT OFFICE.

JOHN M. SLAUGHTER, OF BRIDGEPORT, ALABAMA, ASSIGNOR OF ONE-HALF TO JAMES H. SMITH, OF BRIDGEPORT, ALABAMA.

WEAVING SHUTTLE.

Application filed March 4, 1924. Serial No. 696,790.

To all whom it may concern:

Be it known that I, JOHN M. SLAUGHTER, a citizen of the United States, residing at Bridgeport, in the county of Jackson and 5 State of Alabama, have invented certain new and useful Improvements in Weaving Shuttles; and I do hereby declare the following to be a full, clear, and exact description of the invention, such as will 10 enable others skilled in the art to which it appertains to make and use the same.

The principal object of this invention is the provision of a weaving shuttle which is light, roomy and adapted to be cheaply 15 constructed since it may be cast of metal. Heretofore the shuttle body has been generally constructed of wood and in consequence is heavy and of restricted space for the bobbin.

20 In accordance with the present invention, the shuttle body is adapted to be cast of a suitable material such as aluminum or an alloy thereof, with the result that the walls of the shuttle may be relatively thin, 25 and the ends cored to receive the usual fittings and as a result the shuttle is light, roomy and adapted to be constructed at a minimum cost which is materially less than that involved in the forming of the shuttle 30 of wood.

Other objects and advantages will be apparent and suggest themselves as the nature of the invention is understood.

While the drawings illustrate an embodiment of the invention it is to be understood 35 that in adapting the same to meet different conditions and requirements, various changes in the form, proportion and minor details of construction may be resorted to 40 without departing from the spirit of the invention.

Referring to the accompanying drawings forming a part of the application:

Figure 1 is a top plan view of a shuttle 45 embodying the invention,

Figure 2 is a side view thereof,

Figure 3 is a top plan view of the shuttle body with the fittings removed,

Figure 4 is a detail sectional view on the 50 line 4-4 of Figure 3,

Figure 5 is a detail sectional view on the line 5-5 of Figure 4.

Figure 6 is a detail sectional view on the line 6-6 of Figure 5,

Figure 7 is a detail sectional view on the 55 line 7-7 of Figure 3,

Figure 8 is a detail sectional view on the line 8-8 of Figure 7,

Figure 9 is a detail sectional view on the 60 line 9-9 of Figure 2,

Figure 10 is a detail sectional view on the line 10-10 of Figure 2,

Figure 11 is a detail sectional view on the line 11-11 of Figure 2, looking in the direction of the arrows,

Figure 12 is a detail sectional view on the line 12-12 of Figure 1,

Figure 13 is a bottom view of an end portion of the shuttle,

Figure 14 is a side view of the U-shaped 70 wedge,

Figure 15 is a central longitudinal sectional view of the U-shaped wedge,

Figure 16 is a detail sectional view on the line 16-16 of Figure 14, and

Figure 17 is a detail view of the shim 75 for the spring bobbin holder and coacting retainer.

Corresponding and like parts are referred to in the following description and 80 designated in the several views of the drawings by like reference characters.

The body of the shuttle is designated by the numeral 1 and in external appearance does not differ materially from the ordinary weaving shuttle, opposite ends being tapered to points and an eye 2 provided at one end for the thread and a spring holder 3 being disposed at the opposite end for engaging the bobbin (not shown) in a 85 manner well understood. The body of the shuttle and the end portions thereof are formed with the usual recesses to receive the accustomed fittings and in the present instance, these recesses are cored in the 90 casting of the shuttle, the core being of a shape to correspond with the outline of the recesses, it being understood that the core will be fitted to the flask of the mold in a manner well understood in foundry work 100

in the casting of such articles as require the use of a core. By casting the shuttle body, the walls thereof may be thin and a light metal may be used, such as aluminum or an alloy thereof. The recess 4 at one end of the shuttle body is adapted to receive the usual spring bobbin holder 3, the guide member 5 generally provided for securing the holder 3, and a shim 6. The recess 4 includes an extension 7, the walls of which are outwardly converged to provide for the reception of an approximately U-shaped wedge 8, thereby adapting the spring bobbin holder to the shuttle when the latter is cast of any selected metal preferred for the purpose. This U-shaped wedge 8 is rabbeted upon its lower edge, as indicated at 9, to receive the stem of the shim 6, as indicated most clearly in Figure 12. The bolt 10 usually provided for securing the spring bobbin holder, passes through an opening 11 in opposite sides of the wedge 8, thereby serving to secure the latter when placed in position. The guide member 5 is of ordinary construction and extends along the top, the bottom and in front of the shank of the bobbin holder 3 and the wedge 8. The recess 12 at the opposite end of the shuttle is of a shape to conform to the metal thread guide 13 which directs the thread to the eye 2, said thread guide being made secure by the usual bolt or fastening 14. The bobbin-receiving space 15 and the end recesses 4 and 12 are formed when the

shuttle is cast, by means of a core in a manner well understood by those skilled in foundry work.

What is claimed is:

1. A weaving shuttle having the usual recess at one end to receive the spring bobbin holder and in addition having said recess formed with an extension, a U-shaped element of wedge form in said extension, and a shim in said extension positioning said element. 40
2. A weaving shuttle of cast metal having the usual recess at one end to receive the spring bobbin holder and in addition having said recess formed with an extension, 50 adapted to receive a U-shaped wedge whereby the spring bobbin holder may be adapted to a shuttle cast of any kind of metal, said U-shaped wedge having its lower portion rabbeted to receive the shank 55 of a shim.
3. A weaving shuttle having the usual recess at one end, a spring bobbin holder engaging said recess, the recess formed with an extension, a U-shaped member of 60 wedge shape mounted in said extension and engaging the spring bobbin holder to adapt it to the shuttle, and a shim engaging the lower portion of said wedge.

In testimony whereof I affix my signature in presence of two witnesses.

JOHN M. SLAUGHTER.
